US0D1074669S

(12) **United States Design Patent** (10) **Patent No.:** **US D1,074,669 S**
(45) **Date of Patent:** **** May 13, 2025**

(54) **CODING DEVICE**

(71) Applicant: **FS.COM LIMITED**, Shenzhen (CN)

(72) Inventors: **Zhouwei She**, Shenzhen (CN);
Juncheng Han, Shenzhen (CN)

(73) Assignee: **FS.COM LIMITED**, Shenzhen (CN)

(**) Term: **15 Years**

(21) Appl. No.: **29/837,806**

(22) Filed: **May 9, 2022**

(30) **Foreign Application Priority Data**

Nov. 9, 2021 (CN) 202130734647.8

(51) **LOC (15) Cl.** **14-02**

(52) **U.S. Cl.**

USPC **D14/357**

(58) **Field of Classification Search**

USPC D14/125, 129, 130, 133, 141.1, 141.2,

(57) **CLAIM**

The ornamental design for a coding device, as shown and described.

DESCRIPTION

FIG. 1 is a top, front and right side perspective view of a coding device, showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion taken from FIG. 1; and,

FIG. 10 is an enlarged view of a portion taken from FIG. 2. The broken lines depict portions of the article that form no part of the claimed design.

1 Claim, 10 Drawing Sheets
